Inventor:

Otto H. Van Simberg,
by *Albert G. Davis*
His Attorney.

UNITED STATES PATENT OFFICE.

OTTO H. VAN AMBERG, OF SCHENECTADY, NEW YORK, ASSIGNOR TO GENERAL ELECTRIC COMPANY, A CORPORATION OF NEW YORK.

LUMINOUS ATTACHMENT.

1,355,193.

Specification of Letters Patent. Patented Oct. 12, 1920.

Application filed May 27, 1918. Serial No. 236,706.

To all whom it may concern:

Be it known that I, OTTO H. VAN AMBERG, a citizen of the United States, residing at Schenectady, in the county of Schenectady, State of New York, have invented certain new and useful Improvements in Luminous Attachments, of which the following is a specification.

My invention relates to luminous attachments for indicating to a person entering a dark room the position of a lighting switch or other device. My object is to provide a convenient, sightly device of this character that can readily and safely be secured to existing devices—even when already installed—by persons entirely unacquainted with their construction, without necessity for taking them apart in any way. Various advantages obtainable in connection with my invention will appear from the description hereinafter of the best embodiments at present known to me, while its scope will be indicated in my claims.

In the accompanying drawings, Figure 1 shows one form of device embodying my invention.

Fig. 2 is a sectional view illustrating details of construction and installation.

Fig. 3 is a plan view of the attachment.

Figs. 4 and 5 are similar views illustrating modified forms of construction.

Figs. 6 and 7 are detail views of a part shown in Fig. 5; Fig. 6 an elevation at right angles to Fig. 5, and Fig. 7 a plan view.

Fig. 8 is a sectional view of a modified form of one of the parts.

The device of my present invention is intended for apparatus with pendent cord means—such for example, as electric light switches of the “pull chain” type. It is intended to take the place of the ball usually attached to such chains, and it is so simple that any person can effect the substitution without difficulty.

As will be seen from Fig. 1, the device 5 comprises a glass cup piece 6 adapted to contain suitable luminous material 7,—either in the form of powder, or as a coating painted on its interior surface,—a metal “cover” part 8 to which the cup is secured, and means 9 projecting upward from the part 8 for interlocking with the pull-chain to secure the device thereto, Fig. 2. The cup 6 has a beveled flange or lip 11 at its upper

edge (shown as an enlargement), and the cover 8 has in its center a cylindrical bore 12 and at its lower edge (see Fig. 2) a thin flange 13 depending from an internal shoulder 14 that forms a seat for the upper edge 61 of the cup,—a yieldable disk 15 of heavy paper being interposed and serving as an inner cover immediately overlying and sealing the cup. The cup 6 is secured in the cover 8 by beading or spinning over the 65 flange 13 on the flange portion or lip 11 as at 16. The chain securing means 9 is of a type heretofore in commercial use for securing ordinary metal balls to pull-chains, consisting of a bent-up sleeve of sheet metal 70 with its upper edge bent in (see Fig. 3) so as to leave but a small opening 17 in the center. A little below the upper end in the same side of the sleeve as the slit 18, there is a lateral opening 19, and at its lower end is 75 a flange 21 that lies against a shoulder 22 in the bore 12. Paper or other disks or filling may be inserted in the lower end of the bore 11 to any desired thickness.

To apply the device 5 to an ordinary 80 socket switch chain, it is only necessary to detach the ordinary enlarged ball from the chain and then insert the end ball of the chain sidewise in the opening 19 and force its connecting bar through the slit 18 into 85 the opening 17.

It will be seen that the glower consisting of the cup 6 and the luminous material 7 is equally bright and visible in all directions, (except from almost directly above it, 90 which is an exception of no practical moment), and that the device is neat, convenient, and effective, as well as simple in construction and manufacture. While any self-luminous material may be used, the most 95 satisfactory at present on the market are those which owe their luminosity to radium (or mesothorium) and zinc sulfid; they can easily be made to give the glower a useful life of several years.

In Fig. 4, the cover comprises a short sleeve piece 29 with a flange 30 under the flange 31 of the cup 33 and a washer 34 on which the upper edge of the sleeve 29 is flanged over. The securing sleeve 35 (like 105 that of Figs. 1 and 2) has a flange 36 at its lower end, engaged between the washer 34 and a metal disk 37 that serves as an inner cover for the cup 33.

In Fig. 5, the glass cup 40 has near its 110

upper edge a groove 41, and the cover 42 has its edge beaded over the flange 43 thus formed into the groove. The chain securing means 44 is of wire, bent into a double hook 45 (see Figs. 6 and 7) into the rear side of which the lowermost ball of the pull chain 46 can be sprung. The lower ends of the hook are bent apart so as to be clamped between the metal disk inner cover 47 and the cover 42.

Fig. 8 shows a glass cup 48 differing from that of Fig. 1 only in having a central core 49, which may consist of a short length of glass rod or tubing fused to the bottom of a cup like that in Fig. 1. This is intended for use with a filling of powder, to save the central portion which would be ineffectual and useless. The annular space about the core may have a width of something less than $\frac{1}{16}$ " or $\frac{1}{32}$ ".

What I claim as new and desire to secure by Letters Patent of the United States, is:—

1. A luminous pull-chain attachment comprising a glass cup with a flange portion at its upper edge, said cup containing self-luminous material, a metal cover for said

cup beaded around said flange portion so as to hold the cup securely, an inner cover of yielding material immediately overlying the cup, and means projecting upward from the upper surface of the cover for interlocking with a pull chain to secure the attachment thereto.

2. A luminous attachment as set forth in claim 1 in which the upward projecting securing means has an expanded portion within the cover held between it and the inner cover immediately overlying the cup.

3. A luminous attachment as set forth in claim 1 in which the cover has the form of an inverted bowl with a shoulder above the cup edge and the upward projecting securing means comprises a metal sleeve extending down through the bottom of the bowl and provided with a securing flange.

4. A luminous attachment as set forth in claim 1 in which the glass cup has an integral central core with an annular space for filler around it.

In witness whereof, I have hereunto set my hand this 24th day of May 1918.

OTTO H. VAN AMBERG.
